UNITED STATES PATENT OFFICE.

GEORGE B. LYNCH, OF NEW YORK, N. Y., ASSIGNOR TO JNO. WILLIAMS, INC., A CORPORATION OF NEW YORK.

SHADE-HOLDER.

1,045,417.

Specification of Letters Patent.

Patented Nov. 26, 1912.

Application filed December 30, 1909. Serial No. 535,662.

To all whom it may concern:

Be it known that I, GEORGE B. LYNCH, a citizen of the United States, residing in New York, county of New York, and State of New York, have invented new and useful Improvements in Shade-Holders, of which the following is a description.

My invention pertains to that class of devices known as shade-holders intended to hold a shade or bowl in proper operative relation to some source of illumination.

My invention has for its particular object to provide a shade holder of simple construction by means of which the shade may be readily clamped into position and by a simple operation locked into such position so as to be firmly retained in operative relation to the source of illumination until it is desired that it shall be removed, and it is a further object of my invention that the removal of the shade may be at any time accomplished in a simple and easy manner.

Referring to the drawing, Figure 1 represents a vertical section of a shade holder comprehending my invention. Fig. 2 shows a partial section on the lines 1—2 of Fig. 1 and top plan of a portion of my shade holder. Fig. 3 is a perspective showing in detail one of the members forming a portion of my invention.

In the drawing 1 represents a cylindrical member preferably of light elastic metal and provided with downwardly extending fingers 2 and 3. The fingers 3 are provided with outwardly turned flanges 4 and the fingers 2 are provided with inwardly flanged portions 5, vertical sections 6 and extensions 7 bent to conform with the flange or top of the shade intended to be held in the shade holder as will hereinafter be more fully explained. The portions 6 are provided with outwardly projecting lips or bosses as indicated at 8 which may be "struck up" by means of a proper die from the material of the portions 6. The function of these members 8 will hereinafter be explained.

9 represents an annular ring adapted to slip over the cylindrical portion 1 and rest upon the feet or flanges 4 of the fingers 3.

10 is a metallic ring having cam shaped inner surfaces 11 and adapted to be passed over the fingers 7 until it registers with the vertical portions 6 and is restrained from further movement by the flanges 5.

55 The rings 9 and 10 are united by the spac-

ing members 12, which may be rigidly secured to said rings and one of which members has attached thereto the handle or thumb-piece 13 whereby the said members may be easily rotated. The cams 11 have 60 near their point of smallest diameter slots 14 adapted to engage the members 8 as shown plainly in Fig. 2.

15 represents a portion of the shade held in place by my shade holder. 65

The operation of my improved shade holder is substantially as follows: The member 1 is attached to any suitable type of fixture or support which also carries the source of illumination and to which it is 70 desired to attach the shade. If the handle 13 be swung so as to revolve the rings 9 and 10 into such position that the fingers 7 may expand outwardly to the point of greatest diameter in the ring 10 the shade 15 may 75 then be slipped between the fingers 7 and then if the handle 13 be so moved as to revolve the rings 9 and 10 so that the diameter of the cams 11 in contact with the portions 6 shall decrease, the fingers 7 will be forced 80 inwardly upon the flange of the shade so as to hold the same firmly in place. When the fingers 7 make contact with the flange of the shade 15 further revolution of the ring 10 will cause the portion 6 of the fingers 85 to be forced inwardly and the fingers to yield or spring and when the ring 10 has been sufficiently revolved to bring the members 8 in register with the slots 14 the members 8 will spring into said slots and hold the ring 90 10 from revolving unless considerable force be applied to the handle or thumb-piece 13 thus preventing the shade from rattling out of the holder under the influence of severe vibration as is met in use upon railway trains 95 for which use my shade holder is particularly applicable. If desired to remove the shade the handle 13 has simply to be swung to the increased diameter of the cams 11 when the fingers will open and release the 100 shade. The same may be replaced as above outlined.

From the foregoing it will be obvious that I have produced a shade holder of simple construction and of a strong and durable 105 type which may be manipulated very quickly to grasp or disengage a shade and which when engaging a shade will be locked in its operative position in such manner as not to be rattled loose when vibrated.

I do not wish in any way to limit myself to the exact construction shown in the accompanying drawing which is merely one form of shade holder comprehending my invention for it is obvious that considerable changes may be made in the construction of my shade holder without departing from the spirit of my invention which is as set forth in the following claims:

- 10 1. A shade holder consisting of a base-portion having projecting therefrom shade supporting fingers; a plurality of flanged fingers carried by the base-portion; and movable means supported by said flanged fingers and surrounding said supporting fingers for pressing each finger individually into engagement with a shade.
- 15 2. A shade holder comprising a base-portion provided with depending, shade-supporting means; a plurality of flanged fingers carried by the base-portion; and rotatable means supported by said flanged fingers and having devices for engaging said supporting means adapted to press the latter into engagement with a shade.
- 20 3. A shade holder comprehending a portion provided with projecting fingers with out-turned flanges, a ring resting upon said flanges, a plurality of projecting fingers adapted to engage a shade, movable means for operating said fingers and means uniting said movable means with the above mentioned ring.
- 25 4. A shade holder comprising a base portion, a plurality of flexible fingers project-

ing therefrom and formed at their extremities to engage a shade, rotatable means between the shade engaging portions and the base portion for pressing the said fingers against a shade and rotatable guiding means attached to said operating means so as to revolve therewith.

5. A shade holder comprising a cylindrical member having extending therefrom a plurality of circularly arranged resilient fingers, some of the fingers being longer than the others and the long and short fingers being alternately arranged; extensions carried by the shorter fingers, and the longer fingers being provided with grooved extremities for engaging the flange of a lamp shade, and means carried by the extensions of the shorter fingers and engaging with the longer fingers for altering the position of the latter.

6. A shade holder comprising a cylindrical member having long and short fingers extending therefrom, the short fingers having supporting means and the long fingers having engaging means; a device carried loosely upon the supporting means of the short fingers and engaging the long fingers; and means by which said device may be turned relatively to said fingers to alter the position of the long fingers.
